UNITED STATES PATENT OFFICE.

LEONARD F. FULLER, OF PALO ALTO, CALIFORNIA, ASSIGNOR TO FEDERAL TELEGRAPH COMPANY, OF SAN FRANCISCO, CALIFORNIA, A CORPORATION OF CALIFORNIA.

WIRELESS TELEGRAPHY.

1,179,353.

Specification of Letters Patent. Patented Apr. 11, 1916.

Application filed April 21, 1913. Serial No. 762,475.

To all whom it may concern:

Be it known that I, LEONARD F. FULLER, a citizen of the United States, and a resident of Palo Alto, county of Santa Clara, 5 State of California, have invented certain new and useful Improvements in Wireless Telegraphy, of which the following is a specification.

The invention relates to improvements in 10 wireless telegraphy and especially to improvements in the transmitting circuit.

The object of the invention is to obtain a higher antenna current with a given input than has been heretofore obtained.

15 Another object of the invention is to reduce the resistance of the antenna circuit, thereby increasing the antenna current.

Another object of the invention is to provide means for obtaining sharper tuning 20 than has been heretofore practical.

The invention possesses other advantageous features, which, with the foregoing, will be set forth at length in the following description where I shall outline in full that 25 form of the invention which I have selected for illustration in the drawings accompanying and forming part of the present specification. The novelty of the invention will be included in the claims succeeding said description. From this it will be apparent that I do not limit myself to the showing made by said drawings and description, as I may adopt many variations of the said 30 invention as expressed in said claims.

35 Referring to said drawings: Figure 1 is a diagrammatic representation of one form of the transmitting circuit of my invention. Fig. 2 is a diagrammatic representation of a modified form of the circuit. Fig. 3 is a 40 diagrammatic representation of the closed circuit form of my invention. Fig. 4 is a diagrammatic representation of another modified form of the circuit.

In wireless telegraphy transmitting circuits, a certain amount of energy is not 45 radiated because of the I^2R losses of the source of oscillations. For a given output, a much smaller amount of power is produced in the antenna. By the use of my 50 invention these I^2R losses are greatly reduced and the resistance of the antenna circuit is reduced, with the result that a much higher antenna current is obtained.

The source of oscillations is shown in the 55 present instance as an arc 2, to which power

is supplied by the conductors 3—4 connected to any suitable source of power. In the forms of the invention shown in Figs. 1 and 2, one side of the arc is grounded by the conductor 5. Connected to the other side 60 of the arc is a conductor 6 connected to the antenna 7 and including in circuit in series a capacity, preferably in the form of a variable condenser 8 and a variable inductance 9. Shunted around the variable condenser 8 and the arc 2 is a circuit 11 containing a capacity, preferably in the form of a variable condenser 12. The condenser 8 may be arranged as shown in conductor 6, or it may be placed in conductor 5 between 70 the arc and the point of connection of circuit 11, or two condensers may be used, one in each of the positions stated. The function of the condenser 8 is to produce a voltage to cause the current to pass through 75 the shunt circuit 11, which contains very small resistance and inductance, and charge the condenser 12. Since the impedance of the shunt circuit is much less than that of the arc circuit on which it is shunted, and 80 since the antenna current divides through the arc and shunt circuits inversely as their impedances, the I^2R losses of the arc are accordingly reduced. The capacities of the condensers to be employed depend upon the 85 capacity of the antenna, the power fed to the arc, the ohmic drop through the arc and on the conditions of operation, and are so adjusted to obtain the desired result. Their value is independent of wave length and the 90 shunt circuit is in no wise a tuned circuit. This makes this connection very flexible where a rapid change of wave is desirable.

It is an important feature of this invention that the inductance and resistance of 95 the shunt circuit 11 be kept a minimum, as otherwise the circulating currents through it will not be wattless, as is desired, but will have a power factor of appreciable value. In a circuit in which the arc is more or less 100 unstable and inclined to set up several irregularly dispersed frequencies, this circuit will greatly reduce this tendency, increase the sharpness of tuning and put all of the 105 radiated energy in one wave.

In employing this system in practice, using a 5 K. W. arc, and maintaining the capacities of the antenna and both condensers equal, I have obtained an increase of 50% in the antenna current over the sys- 110

tem in which the antenna current passed entirely through the arc. Using the same installation and doubling the capacity of the condenser 12, I have obtained 100 per cent. 5 increase in the antenna current. The capacity of the condenser 12, however, has a certain maximum critical value above which it fails to aid in boosting the antenna current. Using a 50 K. W. arc I have obtained 10 an increase in antenna power of 74 per cent. over the system in which the total antenna current passed through the arc. The efficiency of the system has been further increased by about 11 per cent., when the 50 15 K. W. arc was in use, by means of the circuits shown in Fig. 2 in which a circuit 13 containing resistance 14, preferably variable, and an inductance 15, preferably variable, is shunted around the condenser 8. If 20 this circuit be tuned nearly into resonance with the oscillations in the main antenna it will have a very high reactive voltage drop across it and will, therefore, force a still greater per cent. of the antenna current 25 through the shunt circuit 11. The resistance of the circuit 13 is comparatively large, allowing a very small current to pass therethrough, so that little energy is consumed therein.

30 It should be noted that the circuit shown in Fig. 1 raises the antenna power by reducing the resistance of the antenna circuit while the circuits shown in Fig. 2 increase the antenna power by greatly reducing the 35 energy losses in the arc.

The modification shown in Fig. 3 operates in the same manner as that shown in Fig. 2, with the exception that the arc circuit is inductively connected to the antenna circuit 40 through the transformer 16, preferably variable, instead of being directly connected thereto. In this system a condenser 18 must be inserted in closed circuit, to produce the capacity effect of the antenna in the open 45 circuits.

50 Signaling is usually accomplished by varying the frequency or the wave length of the radiated oscillations, by varying the inductance in circuit. In the present instance I have shown a key circuit 17 adapted to shunt one or more turns of the inductance 9 or the primary of the transformer.

I claim:

- 55 In a transmission system for wireless telegraphy, a grounded conductor, a source of electrical oscillations, a capacity and inductance in series on said conductor, and a substantially inductionless circuit containing a capacity shunting said first named capacity and the source of oscillations.
- 60 2. In a transmission system for wireless telegraphy, a source of electrical oscillations, a grounded conductor associated

therewith, a capacity in series with said source, and a substantially inductionless circuit containing a capacity shunting said first named capacity and said source. 65

3. In a transmission system for wireless telegraphy, a source of electrical oscillations, a grounded conductor associated therewith, an inductance and capacity in series with said source, a capacity in shunt on said source and first named capacity, and an inductance in shunt on said first named capacity. 70

4. In a transmission system for wireless telegraphy, a source of electrical oscillations, a grounded conductor connected thereto, a capacity and inductance in said conductor, a circuit containing capacity shunting said source and first named capacity, and a circuit containing inductance and resistance in shunt on said first named capacity. 75

5. In a transmission system for wireless telegraphy, an arc, a grounded conductor associated therewith, a capacity and inductance in series in said conductor, a circuit containing capacity shunted around said arc and the first named capacity, and a circuit 90 containing resistance and inductance shunted around said first named capacity. 80

6. In a transmission system for wireless telegraphy, a source of electrical oscillations, a grounded conductor associated therewith, an inductance and capacity in series with said source, and a circuit shunted on said capacity and source, the impedance of said shunt circuit being less than the impedance of the circuit shunted. 95

7. In a transmission system for wireless telegraphy, a source of electrical oscillations, a grounded conductor associated therewith, an inductance and capacity in series with said source, a circuit containing capacity in shunt on said source and first named capacity, and a circuit containing resistance and inductance shunted around said first named capacity, the last shunt circuit being out of resonance with the oscillations in the antenna circuit. 105

8. In a transmission system for wireless telegraphy, a grounded conductor, a source of electrical oscillations, a capacity and inductance in series in said conductor, a substantially inductionless circuit containing a capacity shunting said first named capacity and source of oscillations and means for varying said inductance. 115

In testimony whereof, I have hereunto 120 set my hand at San Francisco, California, this 7th day of April 1913.

LEONARD F. FULLER.
